US00D949133S

(12) **United States Design Patent** (10) Patent No.: **US D949,133 S**
Laffon de Mazieres et al. (45) Date of Patent: **** Apr. 19, 2022**

(54) **PORTABLE INPUT/OUTPUT DEVICE**(71) Applicant: **Amazon Technologies, Inc.**, Seattle, WA (US)(72) Inventors: **Emmanuel J M Laffon de Mazieres**, Burlingame, CA (US); **Giles David Matthew McWilliam**, San Francisco, CA (US); **Marc Rene Walliser**, San Francisco, CA (US)(73) Assignee: **Amazon Technologies, Inc.**, Seattle, WA (US)(***) Term: **15 Years**(21) Appl. No.: **29/747,556**(22) Filed: **Aug. 24, 2020****Related U.S. Application Data**

(62) Division of application No. 29/625,802, filed on Nov. 13, 2017, now Pat. No. Des. 900,795.

(57) **CLAIM**

The ornamental design for a portable input/output device, as shown and described.

DESCRIPTION

FIG. 1 is a top, front, right-side perspective view of a portable input/output device;

FIG. 2 is a front view thereof;

FIG. 3 is a back view thereof;

FIG. 4 is a right-side view thereof;

FIG. 5 is a left-side view thereof;

FIG. 6 is a top view thereof; and,

FIG. 7 is a bottom view thereof.

The dashed broken lines depict portions of the portable input/output device that form no part of the claimed design. The dot-dashed broken lines represent a boundary of the claimed portable input/output device and form no part of the claimed design.

1 Claim, 7 Drawing Sheets(56)
